GARMENT HANGER

Filed March 21, 1930

UNITED STATES PATENT OFFICE

EDWIN C. PERKINS, OF NEW HAVEN, CONNECTICUT

GARMENT HANGER

Application filed March 21, 1930. Serial No. 437,745.

This invention relates to an improvement in garment hangers and particularly to garment hangers which provide a support in which the hanger may be placed, preparatory to placing a garment thereon, and from which support the hanger may be removed and suspended, the object being a simple and convenient arrangement of parts particularly adapting the device for use in closets and other contracted spaces, and the invention consists in the construction as hereinafter described and particularly recited in the claims.

In the accompanying drawings:

Fig. 1 is a face view of a garment hanger constructed in accordance with my invention particularly adapted for trousers;

Fig. 2 is a side view of the same;

Fig. 3 is a plan view of the same;

Fig. 4 is a perspective view of the trousers-hanger, detached;

Fig. 5 is a perspective view showing the garment-hanger plate as connected with a coat-hanger.

In carrying out my invention, I employ a bracket-plate 5 struck up from sheet-metal and affixed to a panel-board 6, or the device may be applied directly to the inner face of a closet door, or to a wall, or wherever desired. The ends 7 and 8 of the plate are turned outward, forming ears, which are formed with horizontal slots 9. The garment hanger comprises a plate 10 corresponding in thickness to the width of the slots 9, and its upper edge is partially cut away, leaving a hook 11.

At each end of the cut-away portion the metal is turned inward, forming lugs 12 adapted to engage with the inner walls of the ends 7 and 8, so that when the plate is entered into the slots 9, the lugs will engage the inner walls of the ends, and thus prevent transverse movement of the plate. For supporting trousers, spring-clips 13 will be attached to each end of the plate, beyond the ends 7 and 8. Attached to the panel 6, or below the bracket-plate 5, is a wire suspension-loop 14 upon which the garment hangers may be suspended.

In use, a hanger is connected with the bracket as above described and is in position

to have the bottoms of a pair of trousers inserted between the clips 13. When so inserted, the hanger is removed from the bracket and hooked onto the suspension-loop 14, from which the trousers may be removed by a downward pull when desired, and after the trousers have been removed, the hanger will again be mounted on the bracket, ready for the replacement of the garment.

For use as a coat or other garment hanger, the clips 13 may be omitted and a plate 16, like the plate 10, connected with a bowed coat hanger 15. The plate 16 will have a hook 17 like the hook 10, and lugs 18 like and for the same purpose as the lugs 12, as indicated in Fig. 5 of the drawings.

In either event, the garment hanger is supported in position to receive a garment and then removed and suspended on the loop 14.

I claim:

1. A garment hanger comprising a bracket having forwardly-extended slotted ends, a plate adapted to be entered horizontally into said slots and formed with a hook by which the plate may be suspended, and means connected with the ends of the plate for supporting a garment.

2. An article of the class specified, consisting of a horizontally-arranged bracket having outwardly-extending ends, the said ends formed with horizontally-arranged slots, a garment hanger comprising a plate adapted to be entered into said slots, the upper edge of the plate cut away, forming a hook by which the plate may be suspended, and means connected with the ends of the plate for supporting a garment.

3. An article of the class specified, consisting of a horizontally-arranged bracket having outwardly-extending ends, the said ends formed with horizontally-arranged slots, a garment hanger comprising a plate adapted to be entered into said slots, the upper edge of the plate cut away, forming a hook by which the plate may be suspended, and a clip connected with each end of the plate for supporting a garment.

4. An article of the class specified, consisting of a horizontally-arranged bracket having outwardly-extending ends, the said

ends formed with horizontally-arranged slots, a garment hanger comprising a plate adapted to be entered into said slots, the upper edge of the plate cut away and formed with lugs 5 positioned to engage with the inner faces of the turned-in ends of the bracket when the hanger-plate is entered between them, and means connected with the ends of the plate for supporting a garment.

10 In testimony whereof, I have signed this specification.

EDWIN C. PERKINS.
